UNITED STATES PATENT OFFICE.

ALBERT BROADMEYER, OF HARRISBURG, PENNSYLVANIA, ASSIGNOR TO W. O. HICKOK MANUFACTURING COMPANY, OF HARRISBURG, PENNSYLVANIA, A CORPORATION OF PENNSYLVANIA.

RULING MACHINE.

Application filed August 14, 1925. Serial No. 50,199.

One of the primary objects of the present invention is to provide novel means of an effective character for lifting the pens from the paper for exceedingly short intervals in order that the lines ruled are broken for very small spaces. Another and important object is to provide means that will act as a brake to allow the beam to return with sufficient speed and yet without jar.

10 In the accompanying drawings:—

Figure 1 is a plan view of a pen beam equipped with the novel mechanism,

Figure 2 is a front elevation of the same,

Figure 3 is a rear elevation,

15 Figure 4 is an end elevation,

Figure 5 is a longitudinal sectional view taken substantially on the line 5—5 of Figure 1,

20 Figure 6 is a sectional view on the line 6—6 of Figure 1,

Figure 7 is a cross sectional view taken on the line 7—7 of Figure 1,

Figure 8 is a detail horizontal sectional view on the line 8—8 of Figure 4,

25 Figure 9 is a detail sectional view on the line 9—9 of Figure 6,

Figure 10 is a horizontal sectional view on the line 10—10 of Figure 9,

Figure 11 is a vertical sectional view on the line 11—11 of Figure 1,

30 Figure 12 is a sectional view on the line 12—12 of Figure 2,

Figure 13 is a detail vertical sectional view on the line 13—13 of Figure 1.

35 In the embodiment disclosed, a portion of a front longitudinal rail 14 and a portion of a rear longitudinal rail 15 of the frame of a ruling machine are shown, and extending across the space between these rails is a pen

40 beam 16, which may be of any desired character. The front end of this beam has an angular head 17, from which projects a

gudgeon 18, and a gudgeon 19^a projects from the rear end of the beam.

45 The gudgeon 18 has rotatably mounted therein the inner end of a horizontal screw 19 that terminates in a head 20. This screw is threaded into a box 21 that is vertically slidable in a post 22. A clamping plate 23,

50 on the outer side of the box 21, has the screw 19 rotatable therein, and threaded on said screw is a locking nut 24 that is arranged to operate against the plate 23 and

cause said plate to coat with the box 21 and grip the post, at the same time also acting as a lock nut for the screw 19. The post 22 is mounted on a slide 25 that operates in a slideway 26 formed in the top of a block 27 that is fastened upon the front rail 14. The post 22 is in the form of a yoke, and journaled in the top cross bar thereof, is a screw 28 having a threaded engagement with the box 21 at one side of the horizontal screw 19, as clearly indicated in Figure 5.

With the above described structure, it will be evident that the pen beam has a pivotal support, so that it can turn on a horizontal axis. By loosening the lock nut 24, the screw 19 can be turned and the pen beam thus shifted longitudinally of said axis. When the nut 24 is tightened the screw will be locked against turning. Furthermore when the nut 24 is loosened, by turning the screw 28 the pen beam can be raised or lowered, and when the nut 24 is tightened, the box 21 will be clamped to the post in its adjusted position. Furthermore by moving the slide 25 in the slideway 26, the front end of the beam can be moved forward or back longitudinally of the rail 14 and it is adapted to be clamped by a set screw 29 threaded through the slide 25 and bearing against the bottom of the slideway.

The rear gudgeon 19 of the pen beam 16 has a universal joint connection 30 with a spindle 31 that extends across the rear rail 15 and terminates at its rear end in an enlarged cylindrical head 32. The spindle is journaled in a box 33 that is vertically adjustable on an outstanding post 34, the portion of the box surrounding the post being split, as shown at 35, and the sections thereof being connected by a tension screw 36. The post 34 is carried by a slide 37 movable in a slideway 38 formed in the top of a block 39 that is fastened longitudinally upon the rear frame rail 15, the guideway 38 being longitudinally of said rail. The slide has a set screw 40, by which it can be held in its adjusted position. The box 33 furthermore has a rearwardly extending split collar extension 41 that surrounds the cylindrical head 32. This collar terminates in a pair of upstanding ears 43, into one of which is threaded a horizontal tension screw 44 that slidably passes through the other ear, and

has a suitable operating head 45. A coiled spring 46, surrounding the screw, is interposed between the head 45 and the adjacent free ear 43.

With this construction the universal joint 30 permits the above described adjustments of the front end of the pen beam and also permits the horizontal and vertical adjustments of the rear end by moving the slide 37 in the slideway 38, and vertically adjusting the box 33 on the post 34. The compressible collar 41 constitutes a brake, the friction of which on the head 32 can be readily varied by moving the screw 44 in one direction or the other, thus putting more or less tension on the spring 46. This mechanism has been found particularly desirable in acting as a brake on the swinging movement of the pen beam, allowing it to drop with sufficient rapidity and yet preventing jars and rebound.

The pen beam is raised and permitted to lower by the usual cams well known in this art, and not shown in detail, but indicated in dotted lines at 47. As usual the pen beam 25 is provided with an arm 48 that is pivoted on the angular head 17, as illustrated at 49, and shown particularly in Figure 6. The position of this arm with relation to the head can be varied and can be fixed by 30 means of the usual adjusting screws 50 threaded through the arm and bearing on the upper side of the head 17. Lock nuts 51, serve to prevent the accidental rotation of the screws. The arm at its free end has 35 a head 52 carrying on its under side a rail plate 53 adapted to be engaged by the usual rotating cam, well known to the art. A stop screw 54, threaded through the arm, is adapted to abut against the stop 55 which 40 limits the downward movement of the arm and consequently the pen beam and a holding dog 56 pivoted on the stop 55 can be swing beneath the screw 54 to hold the pen beam elevated.

The free end of the arm is also provided with an upstanding post 57 having a vertical guideway 58 therein, and in this guideway is slidably mounted a carrier head 59 engaged by an adjusting screw 60 that is 45 threaded thereto and is rotatably mounted in the top of the post, as shown in Figure 9. The carrier head 59 has an outstanding split arm 61 that has threaded therethrough a screw 62, which, as shown in Figure 7, has 50 a reduced unthreaded end 63. A clamping screw 64, connecting the sections of the arm 61, serves to clamp said sections upon the screw 62 and prevent its accidental rotation. The carrier head 59 is also preferably provided with an outstanding threaded stem 65, with which is screwed a clamping nut 66 that serves to cooperate with the post 57, and effectively secure the clamping head 59 in its 55 adjusted position on the post 57. An actuating arm 67 is provided having a sleeve

68 journaled on a pin 68^a that is carried by a bracket 68^b. The bracket 68^b is fixed to the box 21. A coiled spring 68^c fixed to the bracket and to the sleeve 68, serves to urge the arm 67 downwardly. The arm 67 is provided with a roller 69 that is adapted to ride upon one of the usual cams indicated at 47. This arm 67, as illustrated in Figure 7, has upstanding ears 70, between which is an upstanding pawl 71 pivoted to said ears, as 75 illustrated at 72, and having a tail 73 adapted to rest upon the arm. A spring 74 bears against the pawl to urge it rearwardly and yet permit its swinging forwardly. The upper free end of this pawl is so disposed that 80 the unthreaded reduced end 63 of the screw 62 may be positioned in its path.

With this construction, it will be evident that the pen beam can be swung in the usual manner by a cam as 47, operating on the free 85 end of the arm, 48, or if another cam is employed that will swing the arm 69 upwardly, when said arm moves upwardly the pawl 71 will engage the inner end of the screw 62, thus elevating it and thereby 90 through the mounting of said screw, swinging the arm 48 upwardly and giving a corresponding movement to the pen beam. The amount of this movement depends upon the relation of the inner end of the screw 62 95 with respect to the pawl. It can be so arranged that the pawl will just touch it and give a slight movement to the screw, after which the pawl will ride off the end, but can return inasmuch as it can swing rearwardly past said end. A very quick action can thus be obtained which will lift the pens for an instant and permit them to immediately return or the screw can be adjusted to give longer movements and thus create 100 breaks of greater length in the lines being ruled.

From the foregoing, it is thought that the construction, operation and many advantages of the herein described invention will 110 be apparent to those skilled in the art, without further description, and it will be understood that various changes in the size, shape, proportion and minor details of construction, may be resorted to without departing from the spirit or sacrificing any of 115 the advantages of the invention.

What I claim, is:—

1. In ruling apparatus, the combination with a movable pen beam, of an actuated arm carried thereby, an actuating arm, a trip movably mounted on the actuating arm, and means adjustably mounted on the actuated arm for engagement by the trip.

2. In a ruling apparatus, the combination with a movable pen beam, of an actuated arm carried thereby, an actuating arm pivotally supported at one end and having a cam engaging element at its other end, a trip movably mounted on an intermediate 130

portion of the arm, and means adjustably mounted on the actuated arm for engagement by the trip.

3. In a ruling apparatus, the combination with a movable pen beam, of an actuated arm carried thereby, an actuating arm pivotally supported at one end and having a cam engaging element at its other end, a trip pivotally mounted on an intermediate portion of the arm, and a screw adjustably threaded on the actuated arm and having a portion movable to different positions in the path of the trip.

4. In ruling apparatus, the combination with a movable ruling instrumentality, of an actuated arm and an actuating arm, a trip on one arm, and a screw having a threaded mounting on the other arm and having direct engagement with the trip.

5. In ruling apparatus, the combination with a movable ruling instrumentality, of an actuated arm and an actuating arm, a trip on one arm, a mounting adjustably mounted on the other arm, and a device adjustably mounted on the adjustable mounting in a direction transverse to the direction of adjustment of the mounting, said device coacting with the trip to effect the movement of one arm on the movement of the other arm.

6. In ruling apparatus, the combination with a movable ruling instrumentality, of a movable actuated arm, a movable actuating arm, a trip on one arm, a guideway on the other arm, a head movably mounted in the

guideway, and a device movably mounted on the head and coacting with the trip.

7. In ruling apparatus, the combination with a movable ruling instrumentality, of a movable actuated arm, a movable actuating arm, a trip on one arm, a guideway on the other arm, a head slidably mounted in the guideway, means for adjusting the head and holding it, and a screw adjustably threaded on the head and coacting with the trip.

8. In ruling apparatus, the combination with a pivoted pen beam, of an actuated arm mounted thereon, a swinging actuating arm, a trip pivoted on the actuating arm, said actuated arm having a transversely disposed guideway, a carrier head slidably mounted in the guideway, means for fixing the head in the guideway, said head having an arm, and a screw threaded through the arm and having a portion movable to different positions in the path of the trip.

9. In ruling apparatus, the combination with a pen beam and means for operating it, of means for vertically adjusting the beam including a vertically movable box on which the beam is supported, an actuating arm pivotally supported on the box and vertically adjustable therewith, an actuated arm connected to the pen beam, a quick action trip mechanism between the arms, and means for swinging the actuating arm.

In testimony whereof, I affix my signature.

ALBERT BROADMEYER.
